(57) **CLAIM**

The ornamental design for a display screen or portion thereof with animated graphical user interface, as shown and described.

DESCRIPTION

FIG. 1 is a first image of a display screen or portion thereof with animated graphical user interface showing our new design;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof;

FIG. 8 is an eighth image thereof;

FIG. 9 is a ninth image thereof;

FIG. 10 is a tenth image thereof;

FIG. 11 is an eleventh image thereof;

FIG. 12 is a twelfth image thereof;

FIG. 13 is a thirteenth image thereof;

FIG. 14 is a fourteenth image thereof;

FIG. 15 is a fifteenth image thereof;

FIG. 16 is a sixteenth image thereof;

FIG. 17 is a seventeenth image thereof;

FIG. 18 is an eighteenth image thereof;

FIG. 19 is a nineteenth image thereof;

FIG. 20 is a twentieth image thereof;

FIG. 21 is a twenty-first image thereof;

FIG. 22 is a twenty-second image thereof;

FIG. 23 is a twenty-third image thereof;

FIG. 24 is a twenty-fourth image thereof;

FIG. 25 is a twenty-fifth image thereof;

FIG. 26 is a twenty-sixth image thereof;

FIG. 27 is a twenty-seventh image thereof;

FIG. 28 is a twenty-eighth image thereof;

FIG. 29 is a twenty-ninth image thereof;

FIG. 30 is a thirtieth image thereof;

FIG. 31 is a thirty-first image thereof;

FIG. 32 is a thirty-second image thereof;
 FIG. 33 is a thirty-third image thereof;
 FIG. 34 is a thirty-fourth image thereof;
 FIG. 35 is a thirty-fifth image thereof;
 FIG. 36 is a thirty-sixth image thereof;
 FIG. 37 is a thirty-seventh image thereof;
 FIG. 38 is a thirty-eighth image thereof;
 FIG. 39 is a thirty-ninth image thereof;
 FIG. 40 is a fortieth image thereof;
 FIG. 41 is a forty-first image thereof;
 FIG. 42 is a forty-second image thereof;
 FIG. 43 is a forty-third image thereof;
 FIG. 44 is a forty-fourth image thereof;
 FIG. 45 is a forty-fifth image thereof; and,
 FIG. 46 is a forty-sixth image thereof.

The appearance of the animated graphical user interface sequentially transitions between the images shown in FIGS. 1-46. The process or period in which one image transitions to another forms no part of the claimed design.

The outermost, peripheral broken line shows a display screen, or portion thereof, in environment, and forms no part of the claimed design. The other broken lines within the peripheral broken line show other portions of the graphical user interface and form no part of the claimed design.
